UNITED STATES PATENT OFFICE

FRANK E. PAVELKA AND HAROLD W. THOMPSON, OF SAN ANTONIO, TEXAS

DESIGN FOR A GAME TABLE

Application filed November 15, 1930. Serial No. 37,681. Term of patent 7 years.

To all whom it may concern:

Be it known that we, FRANK E. PAVELKA and HAROLD W. THOMPSON, citizens of the United States, residing at San Antonio, in the county of Bexar, State of Texas, have invented a new, original, and ornamental Design for a Game Table, of which the following is a specification, reference being had to the accompanying drawing, forming a part thereof, in which the figure is a perspective view of our new and ornamental game table.

We claim:

The ornamental design for a game table, as shown.

FRANK E. PAVELKA.
HAROLD W. THOMPSON.
